UNITED STATES PATENT OFFICE.

REUBEN STANLEY SMITH, OF MILWAUKEE, WISCONSIN, ASSIGNOR, BY MESNE ASSIGNMENTS, TO FIRST WISCONSIN TRUST COMPANY, A CORPORATION OF NEW YORK.

PROCESS AND APPARATUS FOR MAKING FLANGED CROSSBARS FOR AUTOMOBILE FRAMES.

Application filed October 30, 1920. Serial No. 420,692.

To all whom it may concern:

Be it known that I, REUBEN STANLEY SMITH, a citizen of the United States, and a resident of the city of Milwaukee, county of Milwaukee, and State of Wisconsin, have invented a certain new and useful Improvement in Processes and Apparatus for Making Flanged Crossbars for Automobile Frames; and I do declare the following to be a clear, exact, and complete description thereof, such as will enable persons skilled in the art to which the invention pertains to make and use the same, reference being had to the accompanying drawing for a disclosure as to one form in which the invention has been embodied and by means of which the process may be carried out.

My invention relates to an improved process and apparatus for making curved flanged bars, such, for example, as constitute the cross bars of an automobile or other vehicle frame.

Heretofore, and prior to the development of certain inventions by me, such cross bars have been produced by a series of independent and disconnected operations performed in varying and irregular time and without sequence upon sheet metal blanks, whereby the latter are transformed from their blank state into completed bars, to be assembled later with other elements as a part of the unitary frame structure.

In an application filed by me on Jan. 21, 1918, Serial #212,934, on which Patent No. 1,397,020, was granted November 15, 1921, I have disclosed an assemblage of machines, which by their connected and dependent automatic and simultaneous operation, act to convert sheet metal blanks into frame elements, assemble the elements in their respective positions, and permanently unite the assembled elements into an automobile frame of unitary and rigid structure. In the said assemblage, the various mechanisms operate in synchronism, or in substantial synchronism, in the performance of the functions which they are designed to accomplish, the several sub-divided operations of the preparatory and fabricating operation being simultaneously performed in a single brief period upon the materials in the different stages of their progressive advance-

ment toward completion, the said operating periods alternating with other like periods of brief duration, in which latter the conveying movements of the materials for the progressive treatment described take place, both such preparing and fabricating operation and conveying movement occurring within a brief cyclic period, which is recurrent so long as the assemblage may be in operation.

My present invention resides in a process and apparatus whereby the several operations of punching a curved cross bar blank from a rectangular metal plate or strip, piercing the necessary holes in such blank, turning the side margins of the blank so as to form flanges to reinforce the cross bar, and bending or lapping the projecting ends of the cross bar so as to constitute ears by means of which the cross bars may be united to the side bars of the frame, may be carried on in a succession of operations, all of which are performed in a sub-divided time cycle, as in my said patent. However, in the present case, the operating time cycle is sub-divided by the number of operations performed, and such operations are apportioned so as to take place in succeeding fractional periods of the sub-divided time cycle.

By thus sub-dividing the time cycle, and apportioning the several operations performed in producing a completed flanged cross bar, I am enabled to distribute the load carried by the present apparatus through the whole of the time cycle of operation. By reason of the distribution of the load in the manner described, the usual excessive peak load incident to the synchronous operation of an assemblage like that disclosed in my said patent is avoided, and the apparatus constituting my present invention will operate much more smoothly than will the synchronously operating mechanism of the assemblage referred to. This method of operation also produces a great economy, in that the necessity for the employment of a large motor to carry the excessive peak load is eliminated.

My present invention consists in an assemblage comprising a blanking press for punching out properly contoured cross bar blanks, a piercing press for perforating the

2
said blanks with the necessary number and arrangement of holes, a forming press for turning the side margins of the blanks into planes which stand at an angle to the body 5 of the blank to provide a desirable and necessary reinforcement for the latter, and a lapping press by means of which the projecting ends of the flanged cross bar are turned so as to traverse the plane of the 10 bar and form ears by means of which the said cross bar may be united to the side bars, by rivets or otherwise, to form a rigid and unitary automobile frame.

I propose to actuate the several presses of 15 the present assemblage by means of a main or line shaft driven by a suitable motor, or other means of power. The cycle of operation of the assemblage is sub-divided, and a fractional period of such cycle is allotted 20 to each press for the performance of its particular functions. The driving connections from the main shaft are so adjusted that the presses will operate in a progressive succession upon the cross bar forming 25 materials, each operation occurring within its allotted time, and all of them within the time cycle of the whole operation.

The feeding of the cross bar forming materials into and through the several presses 30 may occur at the conclusion of each cycle of movement. This manner of feeding serves to position a succession of blanks for progressive treatment to completion in the sequence of operations of the presses.

35 In view of the fact that the several presses of the assemblage operate in succeeding periods of an apportioned time cycle, it is desirable that such presses be capable of adjustment in order to secure an even distribution of the load throughout the cycle of operation. To enable this result to be achieved, I have provided means whereby the several presses may be connected and disconnected from the main or line driving 40 shaft and have also provided each press with a separate motor, by means of which the presses may be independently operated for testing purposes, and for securing their proper adjustment with relation to each 45 other, so that the operating movements of the presses, when the latter are to be driven as a unit, may be accurately apportioned in the time cycle. The several motors for driving the presses independently, when the latter are disconnected from the main driving 50 shaft, may be coupled through suitable devices, to their respective presses during the time of such disconnection, and by means of the same devices may be unclutched when 55 it is desired to couple all of the presses to the line shaft so as to operate them as a unit.

In a companion application filed by me 60 concurrently, Serial #420,691, I have disclosed an apparatus somewhat similar to

the present invention, but designed for automatically producing pairs of curved flanged side bars for an automobile frame, which apparatus, although differing in features of construction, has a mode of operation, some of the steps of which are followed in the present apparatus.

Moreover, I have constituted the present assemblage of a series of presses, each of which is provided with a unitary actuating mechanism, such actuating mechanism comprising, among other things, a section of the main or line driving shaft. In setting the several presses in position for operation, the sections of the main driving shaft carried by the press structure will be aligned, and may be coupled as one by means of detachable shaft sections interposed between and coupled to the opposite ends of the already aligned sections of the composite 85 main shaft, to complete the latter. By constructing the presses and portions of their actuating mechanisms as units, I am enabled to quickly effect any necessary adjustment of the relative positions of the 90 presses along the driving line, by use of the portable shaft connecting sections described. In connecting the several sections of the main or line shaft, I find it desirable to use a flexible coupling, by means of 95 which compensation for any slight irregularities of movement will be provided.

The novel features of the invention will be pointed out in the appended claims.

In the drawing which forms a part of 100 this specification:

Figure 1 is a plan view showing diagrammatically the arrangement of the presses forming my improved assemblage, together with the mechanism for driving the presses 105 as a unit, and showing also the means for driving the presses independently of each other.

Fig. 2 is an enlarged view in elevation on the line 2-2, Fig. 3, looking in the direction of the arrow, showing the connections for driving the presses, some of the parts being shown in section for the purpose of making clear the construction of other parts.

Fig. 3 is a sectional view on the line 3-3, 110 Fig. 2, looking in the direction of the arrow, and showing some of the parts in elevation.

Referring now to the drawing, in Fig. 1, the blanking press for punching or cutting suitably contoured cross bar blanks from metal plates or strips is indicated by the letter A; the piercing press for producing in the blank the desired perforations by the letter B; the forming press for turning or drawing the side margins of the blank, so as to form flanges, by the letter C; and the lapping press for turning the projecting ends of the blank, so as to form ears by 120 125 130

means of which the cross bars may be attached to the side bars of the frame, by the letter D.

In the said Fig. 1, the numeral 10 indicates a carrier or conveyor of common construction, which may be actuated with a step-by-step movement so as to feed into and through the presses the cross bar forming elements in spaced relation, such feeding movement taking place at the conclusion of each cycle of progressive operations of the several presses of the group. The extent of the intermittent movement of the carrier or conveyor may be from center to center of the presses, so that with each movement of the said carrier or conveyor a set of cross bar forming elements will be accurately positioned with respect to the dies with which the said presses are equipped.

Referring again to Fig. 1, the numeral 1 indicates one of a series of rectangular metal plates or strips, which are fed into the blanking press A, in the manner described. The dies of this press cut away the marginal portions of the strip, so as to produce the contoured cross bar blank 2, provided with projecting ends 3. The conveyor 10 will carry the blank 2 into the piercing press B, the dies of which will form in the said blank the perforations 4. In the next succeeding movement of the conveyor 10, the now perforated blank 2 is carried into the forming press C, the dies of which will turn or draw the side margins of the blank so as to form the channel bar 5, provided with upstanding flanges 6. With the further movement of the conveyor 10, the channeled bar 5 is carried into the lapping press D, by means of which the projecting ends 3 are bent or turned from the plane of the flanges, so as to form the completed cross bar 7, provided with ears 8, standing at an angle to the longitudinal plane of the cross bar, such ears constituting the means through which the cross bars and side bars may be riveted or otherwise connected together so as to form the frame. After their emergence from the lapping press D, the cross bars may be moved, after inspection, to a point of assembly with the side bars to be fabricated into a completed and rigid structural unit.

A motor 20, of sufficient power to carry the highest peak load which may occur in the cycle of operation of the presses, drives a main or line shaft 21, which latter is coupled to and drives the several presses of the assemblage, when such presses are coupled so as to operate as a group or unit.

The said main shaft is a composite shaft, constructed as hereinafter described. The said shaft is provided with bevel pinions 22 corresponding in number with the presses in the assemblage, each pinion being in

mesh with a bevel gear 23, fixed to the shaft 24 of the press, and by means of which the presses may be operated as a group or unit. The bevel pinions 22 are free to rotate upon the shaft 21, and are provided upon one face of their hubs with clutching means adapted to be engaged by co-acting means formed upon the end of a sleeve 25, splined upon the shaft 21. When the clutch faces of the pinion 22 and sleeve 25 are engaged, the motion of the driving shaft 21 is transmitted to the press. The sleeves 25 may be thrown into and out of clutching engagement by devices now commonly employed in effecting similar movements. The presses may be clutched and unclutched separately, or the clutch actuating means may be coupled so that all of them will be operated at the same time.

A gear 26, upon the back of the bevel gear 23, and also fixed upon the shaft 24, is enclosed by the casing 27, in which the said shaft 24 is journaled.

A motor 30, positioned adjacent each press, has a pinion 31 fixed upon the shaft thereof, such pinion engaging a reducing gear 32, along side of which is a pinion 33, and both mounted upon a short shaft 34, journaled in the casing 27. The pinion 33 is in engagement with a gear 35 fixed upon the shaft 36, also journaled in the casing 27. A pinion 38, rotating loosely upon the shaft 36, is in engagement with the gear 26, and is adapted to be coupled with the shaft, to transmit the motion of the motor 30 to the shaft 24, by means of a sliding clutch member 39, splined upon the said shaft 36, and provided with a clutch face which engages a corresponding face upon the hub of the pinion 38. As in the construction previously described, referring to the clutch sleeve 25, the clutch members 39 may be separately or collectively moved to effect their functions of connecting the presses with the separate motors for independent operation, or for disconnecting the presses when the latter are to be operated as a group or unit.

The provisions described, whereby the presses may be separately and independently operated, will permit them to be moved for the purpose of testing their operation and making any necessary adjustments, after which the several presses may be so set with relation to each other that they will operate in the order and in the timing desired, to distribute the load through the operating cycle of the assemblage. A cover 40 may be used as a guard for the train of reducing gears connecting each independent motor with the shaft of the press.

The main or line shaft 21, is a sectional shaft, composed of relatively fixed and replaceable or portable sections, arranged in alternation. The fixed sections 210 are

journaled in the housings 27, and form a permanent part of the operative connections for driving each of the presses. Intervening sections 211 are used to unite the fixed 5 shaft sections 210, the several alternating sections, when united, forming a continuous shaft. It will be desirable to effect an adjustment of the linear positions of the presses with relation to each other, to meet 10 the requirements of different classes of work. In making such adjustments the presses will be properly spaced and the shaft sections 210 brought into alignment. The distance between the opposing ends of the shaft 15 sections 210, will be filled by the insertion of shaft sections 211 of appropriate length. The alternating shaft sections may be connected by means of a flexible coupling 50, so as to provide a compensation for any slight 20 inequalities of movement which may occur in the operation of the group of presses. I have illustrated such flexible coupling 50 as being composed of flanged discs 51, fixed upon the opposite ends of the shaft sections 25 50 so as to be in proximity when the shaft sections are assembled. To each flanged disc 51 a circular disc 52 is connected, such circular discs receiving and supporting between them at their outer edges a connecting 30 ring 53, the said discs 52 and ring 53 being bolted or otherwise secured together, so that the motion of one shaft section is transmitted through the flexible coupling to the next shaft section, and so on throughout 35 the length of the main or line shaft.

A fly-wheel is indicated at 60, and a clutch, by means of which the motor 20 may be coupled to drive the line shaft 21, is indicated at 61.

40 In the operation of my improved cross bar assembly, the several presses, after independent trial and adjustment, will be so set with relation to each other that they will operate in the respectively apportioned fractions of the time cycle allotted for the operation of the whole. By this means of operating the line or group of presses, the customary excessive peak load usually attendant 45 upon the simultaneous operations of the presses of the group is avoided, and the use of a much smaller driving motor is permissible in achieving the same results. The carrier or conveyor 10, is actuated with a step-by-step feeding movement, so that in 50 each such movement a set of cross bar forming elements in their several stages of completion is advanced and positioned between the dies of the respective presses for the performance of the series or succession of operations upon each set of blanks. The operations of such series or succession are performed in the allotted time cycle, each press 55 performing its function within the fraction of the time cycle of operation apportioned 60 to it, and repeating its operation upon the

stream of the cross bar forming material as the individual units of the latter are fed into and through the several presses. At the conclusion of the succession of movements of the several presses in performing 70 their functions, the whole series of cross bar forming elements is advanced for another cyclic operation of the presses of the assemblage.

I have found it expedient to pierce the 75 blanks while in flat condition, and I prefer to do this in all cases where the location of the perforations with respect to lines upon which the flanges and fastening ears are bent or turned, will permit such piercing 80 without resulting in a distortion of the perforations from the planes in which they should lie in the completed cross bar. But in the case of certain types of cross bars, it is difficult to produce the desired perforations without some of them, at least, being 85 subject to the distortion mentioned. If such distortion takes place in any instance, it becomes necessary to subject the cross bar to further treatment in order to remedy 90 the defect, such remedy usually involving manual treatment, with its resultant expense and the delay usually incident to operations not performed by purely mechanical devices.

In the case of cross bars of the type last described, in which the piercing operation may not be satisfactorily effected while the blank is in its flat state, I have found it desirable to include as a part of the installation, specially adapted piercing presses which are so arranged in the assemblage as to follow the operation of the lapping press, and pierce the necessary holes in the cross bar after the latter has been drawn into its 105 final shape, and with its ears standing in correct angular position, so that any subsequent manual treatment of the cross bar for the purpose of remedying the distortion of the perforations therein will be avoided.

Having thus described by invention, what I claim and desire to secure by Letters Patent of the United States, is:

1. An apparatus for producing flanged cross bars for automobile frames from sheet metal, comprising means for cutting a contoured blank from the said sheet, means for piercing the said blank, means for turning the side margins of the blank to form reinforcing flanges upon the side bar, means for bending the projecting ends of the flanged bar to form fastening ears, and devices for conveying the cross bar forming elements through the apparatus, in combination with driving mechanism actuating all of said means through a succession of operations distributed through the time cycle of operation of the apparatus, whereby an excessive peak load upon the driving mechanism is avoided.

2. An apparatus for producing flanged cross bars for automobile frames from sheet metal, such apparatus comprising separate means for blanking the contoured cross bar elements, piercing the blanks while in flat condition, drawing the longitudinal flanges upon the bars, and lapping the projecting ends thereof to form fastening ears, said means acting in succession upon a plurality of cross bar forming elements to convert each element from a blank into a complete cross bar, and driving mechanism for said means, whereby the latter are actuated in sequence through an operating cycle in which the operations of the several said means are apportioned so as to avoid an excessive peak load upon the driving mechanism, and devices for conveying the cross bar forming elements through the apparatus.

3. An apparatus for producing like flanged cross bars for automobile frames from a spaced set of sheet metal elements, such apparatus comprising means for producing a succession of contoured blanks therefrom, means for converting the blanks into flanged bars, and means for bending the projecting ends of the bars to form fastening ears thereon, in combination with driving mechanism for said means, whereby the latter are actuated in sequence through an operating cycle in which the operations of the several said means in the performance of their functions are distributed so as to avoid an excessive peak load upon the driving mechanism, and devices for conveying the cross bar forming elements through the apparatus.

4. An apparatus for producing flanged cross bars for automobile frames from sheet metal, such apparatus comprising means acting separately and by successive operations upon a set of sheet metal elements to progressively convert the latter into completed bars, and driving mechanism for actuating the said conversion means through a time cycle in which the operation of the said means is sub-divided and apportioned so as to avoid an excessive peak load upon the driving mechanism, and devices for conveying the cross bar forming elements through the apparatus.

5. An apparatus for producing flanged cross bars for automobile frames from sheet metal, such apparatus comprising means for acting upon blank forming material to produce a succession of blanks, and other means acting progressively upon said succession of blanks by a series of operations whereby the blanks are converted into completed bars, in combination with driving mechanism for actuating all of said means through a time cycle in which the operation of said means is apportioned so that an excessive peak load upon the driving mech-

ism is avoided, and devices for conveying the cross bar forming elements through the apparatus.

6. An apparatus for producing flanged cross bars for automobile frames, comprising a line of presses adapted by successive operations performed upon the cross bar elements as the latter are fed from press to press to progressively produce cross bar blanks, pierce the latter, draw the side margins of the blanks to form flanges, and bend the projecting ends to form fastening ears thereon, in combination with driving mechanisms for the said presses connected to actuate the latter for the performance of the said progressive operations in a subdivided time cycle in which the progressive operations are apportioned, so that the load upon the driving mechanism is distributed and equalized throughout the operating cycle, and an excessive peak load thereby avoided, and devices for conveying the cross bar forming elements through the apparatus.

7. An apparatus for producing flanged bars for automobile frames from sheet metal, such apparatus comprising a series of consecutively operating presses provided with dies adapted to perform in succession the progressive operations in converting the metal blank into a completed bar, a shaft section embraced within the driving mechanism for each press, means for connecting the said shaft sections so as to constitute a line shaft, and means for actuating the said line shaft to operate the presses in succeeding portions of a time cycle, whereby an excessive peak load upon the actuating means is avoided, and devices for conveying the cross bar forming elements through the apparatus.

8. An apparatus for producing flanged cross bars for automobile frames from sheet metal, comprising a series of presses adjustable with relation to each other and provided with dies adapted to perform a succession of operations upon the cross bar forming elements to convert the latter into completed bars, a sectional line shaft and means for driving the same for actuating the presses as a whole, said line shaft being constituted of sections which form a part of the actuating mechanism for each press and replaceable sections intermediate the first named sections, and flexible connections between the respective shaft sections to compensate irregularities in the setting of the presses with relation to each other, and devices for conveying the cross bar forming elements through the apparatus.

9. The method of producing flanged cross bars for automobile frames, which consists in feeding a succession of element forming material along a line of travel, blanking and piercing such elements, turning side

flanges thereon and bending the projecting ends thereof to form fastening ears, all in a series of operations performed progressively upon the advancing elements, in a sub-divided time cycle in which the progressive operations are apportioned and an excessive peak load upon the driving means is avoided.

10. The method for producing flanged cross bars for automobile frames which consists in cutting contoured blanks from metal plates or strips, piercing such blanks, turning the side margins thereof to form flanges, and bending the projecting ends of the blanks to form fastening ears, advancing the said blanks for the progressive performance of the said operations, all in a brief cyclic period in which the operations are apportioned so as to avoid a peak load upon the driving means.
15. The method of producing flanged cross bars for automobile frames, which consists in feeding a succession of bar forming elements along a single line of travel, subjecting the said elements to different operations in a sub-divided time cycle at the several stations in their travel but to like operations at the same stations, whereby the elements are progressively converted into completed cross bars by a series of operations performed in sequence in which the said several operations are apportioned so

as to avoid an excessive peak load upon the driving means.

12. The method of producing flanged cross bars for automobile frames, which consists in feeding a succession of sheet metal elements and subjecting them to a series of progressive converting operations whereby such elements are formed into finished cross bars, such progressive converting operations being performed in succeeding fractions of a time cycle through which the said operations are apportioned so as to avoid an excessive load upon the driving means.

13. The process of progressively producing flanged cross bars for automobile frames, which consists in conveying sheet metal material along a single line of travel, subjecting such material to treatment, including automatic piercing and shaping, to form completed cross bars in a series of sub-divided operations performed at successive stages of its advancing movement, and distributed through a time cycle in which such operations are apportioned so as to avoid an excessive peak load upon the driving means.

In testimony whereof, I have signed my name at Milwaukee, this 27th day of October, 1920.

R. STANLEY SMITH.
